C. T. BYRD

ICE CREEPER

Filed Aug. 6, 1921

Charlie T. Byrd Inventor

By A. Randolph, Jr.
Attorney

UNITED STATES PATENT OFFICE.

CHARLIE TRUITT BYRD, OF ATLANTA, GEORGIA.

ICE CREEPER.

Application filed August 6, 1921. Serial No. 490,287.

To all whom it may concern:

Be it known that I, CHARLIE T. BYRD, a citizen of the United States, residing at Atlanta, in the county of Fulton and State of Georgia, have invented certain new and useful Improvements in Ice Creepers; and I do hereby declare the following to be a full, clear, and exact description of the invention, such as will enable others skilled in the art to which it appertains to make and use the same.

This invention relates to an anti-slipping attachment for shoes designed particularly to facilitate walking upon ice.

15 An important object is to provide a plurality of plates capable of movement to simulate the action of a shoe sole, which sections are attachable to and detachable from the shoe, are hinged together and have 20 spring means to maintain them normally aligned, and have spurred means preferably detachably secured thereto.

Additional objects and advantages will 25 appear hereinafter from the description of an operative embodiment taken in connection with accompanying drawings:

In said drawings:—

Fig. 1 is a side elevation of the attachment or creeper in place on a shoe;

30 Fig. 2 is a longitudinal sectional view through the attachment on line 2—2 of Fig. 1, and

Fig. 3 is a bottom or inverted plan view of the attachment.

35 Referring specifically to the drawings, wherein like reference characters designate like or corresponding parts in the different views thereof a conventional shoe is suggested at A and the attachment may comprise a heel plate 4 and a sole plate 5 which are preferably metallic and pivoted together by a pintle 6 passing through barrels 7 of the plates at the instep of the shoe. Said plates 4 and 5 may be secured to the shoe in any 40 desired manner as by means of a strap 8 on each plate in separable sections connectible by buckles 9. Plate 4 has an upstanding marginal wall 10 to surround the heel and slots 11 are provided therethrough for connection of the adjacent strap 8. One or 45 more leaf springs 12 are secured at 13 to one of the plates and extend through adjacent 50

barrels 7 where cut away as at 14 to guide and protect the springs and engage the opposite plate so as to normally maintain the 55 plates in contact with and urge them against the heel and sole respectively. This construction particularly cooperates with a single strap fastening such as 8 for each section as sagging at the pintle 6 would 60 occur if the spring 12 did not urge the sections to normal position, that is, in such relation where they jointly conform to the shape of the sole and heel. Plate 4 at 15 extends upwardly in front of the heel of the 65 shoe and at 16 a nose is provided on the plate 5 to clip over the toe of the shoe sole.

It is to be noted that the pintle 6 and barrels 7 and springs 12 are disposed below the upper surface of plates 4 and 5 so as to 70 enable intimate flat contact of plates 4 and 5 at their junction against the shoe sole.

Means to directly engage the ice are provided on the plates 4 and 5 and may be in the form of plates 17, preferably removably secured to said plates 4 and 5, as by means of bolts 18. These plates 17 are preferably of sheet metal and have ice-penetrating spurs or carks 19, of any desired size, length or shape struck out therefrom. 75 By having removable plates provided with these spurs, they can be discarded and new ones substituted without discarding the entire attachment. The spurs 19 can also be more expeditiously sharpened when the 80 plates 17 are detached.

In use, the straps 8 are buckled about the shoe to mount the attachment so that as the wearer thereof walks upon ice, the spurs 19 will penetrate the ice, and prevent slipping or falling. At the same time the plates 4 and 5 at pintle 6 flex to correspond with flexure of the shoe sole, being always urged against such sole by the springs 12.

Since merely one embodiment has been 95 illustrated, and described, it is to be understood that changes in the details of construction may be resorted to within its spirit and scope.

What is claimed is:—

1. An anti-slipping attachment for shoes consisting of plates, means below the upper surface of the plates to pivot them together to yield with a sole of a shoe, anti-slipping

means on said plates, and spring means associated with said hinge to prevent sagging of the plates.

2. An anti-slipping attachment for shoes having plates, barrels depending from the plates, a pintle joining the barrels, one of said barrels being cut-away above the pintle and a spring in said cut-away barrel above

the pintle and overlapping both plates to prevent sagging of the plates.

In testimony whereof I affix my signature in presence of two witnesses.

CHARLIE TRUITT BYRD.
